Primary Examiner — Michael C Stout*Assistant Examiner* — Laura H Yu(74) *Attorney, Agent, or Firm* — Goldstein Law Offices, P.C.(57) **CLAIM**

The ornamental design for a calendar, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of the calendar arranged with the first through sixth calendar month pages arranged together as a group.

FIG. 2 is a front elevational view of the first calendar month page.

FIG. 3 is a front elevational view of the second calendar month page.

FIG. 4 is a front elevational view of the third calendar month page.

FIG. 5 is a front elevational view of the fourth calendar month page.

FIG. 6 is a front elevational view of the fifth calendar month page; and,

FIG. 7 is a front elevational view of the sixth calendar month page.

The calendar is printed on flat material with no substantial thickness.

The broken lines showing in FIGS. 1 through FIG. 7, indicating areas that would contain day, week, and month specific text, form no part of the claimed design.

1 Claim, 7 Drawing Sheets
(7 of 7 Drawing Sheet(s) Filed in Color)
